United States Patent Office

Des. 189,310
Patented Nov. 22, 1960

189,310

PEPPER MILL OR SIMILAR ARTICLE

Burnie M. Craig, Pasadena, and Norman E. Roe, Sierra Madre, Calif., assignors to The George Thompson Corporation, South Pasadena, Calif., a corporation of California

Filed Nov. 12, 1959, Ser. No. 58,316

Term of patent 14 years

(Cl. D44—22)

Fig. 1

Fig. 2

Fig. 3

Figure 1 is a side elevational view of a pepper mill or similar article, showing our new design.

Figure 2 is a top plan view of the pepper mill or similar article shown in Figure 1.

Figure 3 is a bottom plan view of the pepper mill or similar article shown in Figure 1.

We claim:

The ornamental design for a pepper mill or similar article, substantially as shown.
